Specification for Design.

Patented Jan. 9, 1906.

Application filed December 1, 1905. Serial No. 289,924. Term of patent 3½ years.

To all whom it may concern:

Be it known that I, FRANCIS SCHENKER, a citizen of the United States, residing at Vincennes, in the county of Knox, State of Indiana, have invented a new, original, and ornamental Design for Condiment-Holders, of which the following is a specification, reference being had to the accompanying drawings, forming part thereof.

Figure 1 is a perspective view taken at one side of the condiment-holder, showing my new design. Fig. 2 is a rear perspective view of the same.

I claim—

The ornamental design for a condiment-holder, as shown.

F. SCHENKER.
